UNITED STATES PATENT OFFICE.

STERLING ELLIOTT, OF NEWTON, MASSACHUSETTS,

1,047,012.

Specification of Letters Patent.

Patented Dec. 10, 1912.

Application filed October 21, 1910. Serial No. 588,355.

To all whom it may concern:

Be it known that I, STERLING ELLIOTT, residing at Newton, in the county of Middlesex and State of Massachusetts, have invented an Improvement in Oil-Cups, of which the following is a specification.

This invention has reference to oil-cups, and particularly to the closing means therefor.

10 The invention has for its object to construct an improved self-closing device for an oil-cup comprising a disk having an annular seat to engage the top of the cup, and also having a conical boss centrally disposed 15 within said seat to enter the opening at the top of the cup and to serve as self-centering means for the disk when resuming its normally closed position, and also having an ear at the apex of the boss, and a spring 20 connected at one end to said ear which extends lengthwise through the cup and is connected at its opposite end to a cross-bar which is arranged in an annular recess at the bottom of the cup and which admits of a 25 rotary movement of the disk and spring relative to the cup, so that in case the disk should be turned accidentally or otherwise, the spring will not be unduly strained, and the end connection of the spring with the 30 ear is sufficiently remote from the boss to provide a space therebetween, so that said ear may engage the edge of the top of the body and rock thereon when the disk is tipped to open and close the cup and to admit of said disk being tipped up into approximately a vertical position to open wide 35 the top of the cup.

The invention also has for its object, to connect a non-extensible link with the spring 40 by which extension of said link is limited, said link, however, being connected with the spring so as to admit of rotation with the spring and disk whenever the disk is turned with respect to the cup.

45 Figure 1 is a side elevation of an oil-cup embodying this invention. Fig. 2 is a vertical section of the same. Fig. 3 is a view similar to Fig. 1, the closing-disk being tipped up into vertical position to open the 50 cup at the top. Fig. 4 is an under side view.

a represents the cylindrical tubular body of the cup having a threaded end portion and a hexagonal intermediate portion.

55 *b* represents a closing-disk for the top of the cup, which, as here shown has a conical boss *b'* on its under side to enter the opening

at the top of the cup and an ear *b''* at the apex of said boss, and an annular seat *b'''* surrounding said boss to engage the top of the cup.

c represents a coiled-spring which has coils at its upper end to connect it with the ear *b''*, and said spring is made long enough to extend through the cup and has coils at its lower end to connect it to a cross-bar *c'*. Said cross-bar extends diametrically across the bottom of the cup and is arranged in an annular recess *c''* formed in the cup at the bottom. Said cross-bar is free to be turned in said recess, so that in case the disk *b* is turned accidentally or otherwise, the spring will not be unduly strained and its efficiency thereby impaired, as would be the case if the lower end of the spring was connected by fixed means to the bottom of the cup. Said spring is smaller in diameter than the opening through the body adapting it to be moved into an inclined position to permit the disk to be tipped up into vertical position, as shown in Fig. 3, to open the cup at the top, and said spring acts to immediately return the disk to normal position as soon as said disk is released. The disk when resuming its normal position is centered by the conical boss so that it becomes properly seated on top of the cup. The upper end connection of the spring with the ear is sufficiently remote from the boss to provide a space therebetween so that said ear may engage the edge of the top of the cup and act as a fulcrum-lever when the disk is tipped upwardly to open the top of the cup and to admit of said disk being tipped up into vertical position to open wide the top of the cup. It will be noted that the distance between the end connection of the spring with the ear and the boss is approximately as great as the thickness of the wall of the tubular body and the ear is thus adapted to rock on the edge of the top of the cup. The cross-bar is detachably connected with the spring by reason of extending through the coils at the lower end thereof, but is held in the annular recess by the spring. To prevent the disk from being lifted or tipped up so far as to unduly strain and thereby impair the efficiency of the spring, a non-extensible link *d*, composed, as here shown, of wire, is provided,

100 which is arranged at the side of the spring, and said link is made longer than the spring, and its ends *d'* and *d''* are bent over to form

hooks which extend into the openings in the opposite ends of the spring, as for instance, said ends d' and d'' may extend through the coils, as represented in Fig. 2. Said link, 5 however, is quite independent of the spring and permits said spring to be extended, but acts to limit its extension. In case the disk is turned and the spring is turned with it, the link which is connected at its ends with 10 the spring also will be turned.

I claim:—

The oil-cup herein described consisting of a tubular body, a self-closing disk at the top thereof having on its under side an annular seat to engage the top of said body, and a conical boss arranged within said seat having an ear at its apex, a spring extended through said body which is connected at one end to said ear, and means to rotatably connect the other end of said spring 15 20

with the body, the end connection of said spring with the ear being sufficiently remote from the boss to provide a space therebetween to admit of the ear engaging the edge of the top of the cup and rocking thereon as the disk is tipped to open and close the cup, and to admit of said disk being tipped into a vertical position to open wide the top of the cup, and a link contained in said tubular body which is made longer than the 25 30 spring having hooks at its ends to provide for sliding engagement with the spring whereby extension of the spring is limited.

In testimony whereof, I have signed my name to this specification, in the presence 35 of two subscribing witnesses.

STERLING ELLIOTT.
